US00D670562S

(12) **United States Design Patent**
Lembke

(10) **Patent No.:** **US D670,562 S**
(45) **Date of Patent:** **** Nov. 13, 2012**

(54) **BOTTLE**

(75) Inventor: **Bryan James Lembke**, Crystal Lake, IL (US)

(73) Assignee: **Tropicana Products, Inc.**, Bradenton, FL (US)

(**) Term: **14 Years**

(21) Appl. No.: **29/404,711**

(22) Filed: **Oct. 25, 2011**

Related U.S. Application Data

(62) Division of application No. 29/337,180, filed on May 15, 2009, now abandoned.

(51) **LOC (9) Cl.** **09-01**

(52) **U.S. Cl.** **D9/516; D9/567; D9/569; D9/570**

(58) **Field of Classification Search** D9/516, D9/538, 541-542, 547, 554, 556-557, 560, D9/565-567, 569-571, 574, 682, 685, 693-694; 215/379, 381-384; 220/672, 673; D24/197

See application file for complete search history.

(57) **CLAIM**

The ornamental design for a bottle, as shown and described.

DESCRIPTION

FIG. 1 is a top, front, right side perspective view of a first embodiment of a bottle showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is a top, front, right side perspective view of a second embodiment of a bottle showing my new design;

FIG. 9 is a front elevational view thereof;

FIG. 10 is a right side elevational view thereof;

FIG. 11 is a rear elevational view thereof;

FIG. 12 is a left side elevational view thereof;

FIG. 13 is a top plan view thereof; and,

FIG. 14 is a bottom plan view thereof.

The dash-dash-dash-dash broken lines shown in the drawings are included for the purpose of illustrating environmental structure and form no part of the claimed design.

The dot-dash-dot-dash broken lines shown in the drawings represent the unclaimed boundaries of the claimed design.

The oblique shade lines shown in the drawing views indicate a transparent surface.
